UNITED STATES PATENT OFFICE.

WILLIAM H. LIKINS, OF JACKSON, ASSIGNOR OF ONE-HALF TO ALLEN W. ATTERBURY, OF DETROIT, MICHIGAN.

MIDDLEINGS-PURIFIER.

SPECIFICATION forming part of Letters Patent No. 348,754, dated September 7, 1886.

Application filed January 29, 1886. Serial No. 190,186. (No model.)

To all whom it may concern:

Be it known that I, WILLIAM H. LIKINS, of Jackson, in the county of Jackson and State of Michigan, having invented new and useful Improvements in Middleings-Purifiers; and I do hereby declare that the following is a full, clear, and exact description thereof, reference being had to the accompanying drawings, which form a part of this specification.

10 This invention relates to certain new and useful improvements in middleings-purifiers; and the invention consists in the novel combinations and the peculiar construction and arrangement of parts, all as more fully herein-
15 after described, and specifically set forth in the claims.

In the drawings which accompany this specification, Figure 1 is a front elevation of my improved purifier. Fig. 2 is a vertical central cross-section on the line *x* *x* in Fig. 1. Fig. 3 is a horizontal section on the line *y* *y* in Fig. 1. Fig. 4 is an enlarged section of one of the middleings-purifiers proper.

A revolving reel, A, inclosed in a proper case, B, is supported by a suitable frame and forms the upper portion of the machine. This reel may be of any of the known descriptions used for bolting, and is covered with cloth of different grades of fineness.

30 Care cant-boards which direct the middleings bolted through the reel to the conveyer. D and E are spouts into which the conveyer carries the middleings. The conveyer is preferably so arranged that each grade of middleings is carried to one of the spouts only and conducted by it to the purifiers proper, of which there is one to every spout. These purifiers are all of like construction, and are arranged as follows: Each of the spouts E extends down-

40 ward and connects at its lower end with a cylindrical chamber, F, of which the discharge end of the spout forms the eye. Concentrically within this chamber and near the top thereof, so as to form passages N O, is placed the horizontal revolving disk G, which is secured on a vertical shaft, H. The shaft H is held in suitable bearings, and is provided with a pulley, I, by means of which motion is transmitted to this shaft from the main shaft J.
45 50 Below the revolving spreader-disk G is secured the stationary cylindrical wall K, pro-

vided at its lower end with an outwardly-deflecting flange, L, all so arranged as to form between said deflector and the cylindrical wall of the chamber F an annular passage, M, which connects with the passages N O and forms a vertical downward continuation thereof, terminating in an outward annular discharge-opening, P, below the cylindrical wall of the chamber F.

R is a cylindrical case concentrically inclosing the above-described parts. It is provided at its lower end with an inwardly-inclined flange, S, and at its upper end with a conical hood, T, all so arranged as to form an outer annular air-passage, U, which at its upper end connects with the trunk-flue V. The lower end of this passage extends beyond the annular opening P and communicates with the outer air through the annular opening Y, left between the flange S, and the hopper Z, secured below it. The hopper Z has a discharge-opening into the conveyer a, which latter is placed underneath and connects with all the other purifiers in a similar manner. The trunk-flues V are all connected with the flue b, and suitable valves, d, are placed in these connections. The flue b, which leads to a suction-fan, c, is also provided, preferably, with one or more separator-trunks, e, which at their lower ends have discharge-openings provided with hinged valves f into another conveyer, g. The power is preferably conveyed to the main shaft I, supported in suitable bearings on the front side of the machine, and from there it is transmitted by suitable belts or chains to the other operating parts.

The operation of this machine is as follows: The middleings are fed to the bolting-reel A, which is constructed and arranged to operate in the usual manner. The material passing through the cloth into the conveyer-trough underneath is carried, each grade separately, into the spouts E, which conduct the material to the purifiers proper. These purifiers all operate in like manner, and each one for itself performs a complete operation. The material falls through the spout E on top of the revolving disk G and near the center thereof, and by centrifugal force, which is quickly imparted to it by the high speed with which said disk revolves, it is thrown outwardly, and at the

same time is spread in a thin and even sheet. In this form it falls into the annular passage M, and is then deflected outwardly by the flange L through the opening P. Being still 5 farther spread thereby, and at the same time having lost its momentum, it is struck by a current of air produced by the suction. This current of air passes in through the annular opening Y, and takes its course upwardly to 10 toward the passage U, where it strikes the material, spouting out through the opening P at a right angle, or nearly so, enabling it to load itself with all the impurities and carry them away in an upward direction, while the purified middlings fall to the bottom and are directed by the flange S into the hopper Z, which 15 discharges them into the conveyer a. The material in dropping from the flange S into the hopper is thus traversed a second time by 20 an air-current. The impurities carried off by the air-current are conducted upward through the passage U into the trunk V, from which they are drawn through the air-flue b into the suction-fan and discharged from there.

25 By means of the valves d the air-currents passing through each purifier can be regulated to act in the best manner, and should any good material be carried up into the suction-flue b it will there drop out of the air-current into the separator-trunks e, which, 30 for this purpose, are suitably arranged to collect such material and discharge it into a separate conveyer, g, from which it is disposed of in any desired manner for further reduction.

35 It will be seen that as many of the purifiers proper as desired may be combined in a single machine, and the purified product of each may be singly collected and delivered to to the proper rolls for further reduction.

40 It is evident that the construction of the machine described may be variously modified within the spirit of my invention.

45 My improved machine is able to accomplish a much larger amount of work compared with other machines of equal size in present use, and as floor-space is a great desideratum in mills the advantage gained thereby is obvious.

What I claim as my invention is—

50 1. In a middlings-purifier, the combination of the feed-spout E, conveyer D at the entrance of said spout, the cylindrical case R, the rotary disk G, arranged to spread the material by centrifugal force, the cylindrical

partition F, forming annular passages M U, 55 said passage M arranged to receive and carry the material, the lateral discharge-spout P, and means for producing an upward air-current through passage U, all arranged and operating substantially as described. 60

2. In a middlings-purifier, the combination of the horizontal revolving disk G, the cylindrical case R, the cylindrical partition F, placed concentrically to the case and disk and forming therewith and the wall K the 65 passages N U O, the central feed-spout, E, connecting with said passage N, the cylindrical wall K, having outwardly-deflecting flange L, and forming the passage M and the annular discharge-opening P, and means for 70 producing an upward air-current, all arranged and operating to spread the material, substantially as described.

3. In a middlings-purifier, the combination, with the disk G, partition F, wall K, 75 and the concentric inclosed case R, all arranged, as described, to form the passages N U O, of the inwardly-inclined flange S at the lower end of said case, the hopper Z below 80 said flange, having an annular opening, Y, between the same, and means for producing an upward air-current, substantially as and for the purpose specified.

4. In a middlings-purifier, the combination, with the rotary disk G, cylindrical wall 85 K, partition F, and case R, constructed and arranged to form the passages N U O, as described, of the trunk V, communicating with the passage U, outwardly-deflecting flange L at the lower end of the wall K, inwardly-inclined flange S at the lower end of the case R, the hopper Z below said flange S, having 90 an annular opening, Y, between said flange and hopper, and means for producing an air-current through passage U and trunk V, substantially as and for the purpose specified. 95

5. The combination, with the flue b and the trunk-flues V, connected with said flues, of valves d at the points of connection of said flues, separator-trunks e, each provided with a hinged valve, f, and the conveyer g, all combined, arranged, and operating substantially as and for the purposes specified. 100
